UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A PITCHER.

Application filed June 17, 1921. Serial No. 478,452. Term of patent 14 years.

To all whom it may concern:

Be it known that I, ANDREW J. SANFORD, a citizen of the United States of America, residing at Newark, in the county of Licking and State of Ohio, have invented a new, original, and ornamental Design for Pitchers, of which the following is a specification, reference being had to the accompanying drawing, forming part thereof.

The drawing illustrates the physical embodiment of my invention as a molasses can with a lid thereon.

Figure 1 is a side view of the pitcher embodying the subject matter of my invention.

Figure 2 is a view in rear elevation of the design as embodied in Figure 1.

I claim:

The ornamental design for a pitcher, as shown.

ANDREW J. SANFORD.
